UNITED STATES PATENT OFFICE.

WILLIAM YOUNG, OF EASTON, PENNSYLVANIA.

WATER-GAGE.

SPECIFICATION forming part of Letters Patent No. 333,046, dated December 22, 1885.

Application filed March 27, 1885. Serial No. 160,334. (No model.)

To all whom it may concern:

Be it known that I, WILLIAM YOUNG, of Easton, in the county of Northampton and State of Pennsylvania, have invented a new and Improved Water-Gage for Steam-Generators, of which the following is a full, clear, and exact description.

Reference is to be had to the accompanying drawings, forming part of this specification, in which similar letters of reference indicate corresponding parts in both the figures.

Figure 1 is a broken side elevation of my new and improved water-gage; and Fig. 2 is a sectional plan view of the same, taken on the line *x x* of Fig. 1.

My invention consists of a water-gage having an inner and outer glass tube, whereby sudden changes of temperature will not break the glass tube, as it is liable to do with the gages of ordinary construction.

Referring to the drawings, A B represent the upper and lower globe-valves by which the water-gage is connected to the boiler.

C is the inner, and D the outer, glass tube. The inner tube, C, is connected at its ends to the globe-valves A B by the elbows E, short pipes F, and coupling-nuts G, the ends of the tube C being connected to the elbows by the stuffing-boxes H. The stuffing-boxes H are each cupped, as shown at *h*, to receive the ends of the outer tube, D, where they are held by the surrounding stuffing-boxes or packed nuts J, screwed upon the outer surfaces of the boxes

H. An opening, *i*, is formed in the stuffing-box H, to admit a slight circulation of air to 35 and from the space *j*, between the inner and outer tubes, so that with this exception the inner tube is perfectly protected by the outer tube from violent drafts of cold air, which otherwise would be liable to break the tube C 40 when heated by hot water and steam from the boiler.

To protect the tubes C D, I employ the guard-rods K K, held in the plates L L, formed upon the elbow-pipes E, in the ordinary way. 45 The outer tube, D, also serves to magnify the contents of the tube C, so that the condition of the boiler may be easily and more accurately ascertained than with ordinary single glass gages.

Having thus described my invention, I claim as new and desire to secure by Letters Patent—

1. A water-gage consisting of two concentric glass tubes, C D, having a space, *j*, between them, the inner one, C, communicating 55 only with the steam-passages, substantially as herein shown and described.

2. In a water-gage, the boxes H, for securing the inner tube to the elbows E, formed with cups *h*, in combination with the outer 60 tube, D, and nuts J, arranged substantially as and for the purposes set forth.

WILLIAM YOUNG.
